UNITED STATES PATENT OFFICE

OSCAR G. SCHAAF AND FREDERICK WILLIAM CHRISTIANSEN, OF SEATTLE, WASHINGTON, ASSIGNORS, BY MESNE ASSIGNMENTS, TO ELLIOTT-FISHER COMPANY, OF NEW YORK, N. Y., A CORPORATION OF DELAWARE

COMBINED TYPEWRITING AND COMPUTING MACHINE

Application filed May 6, 1926. Serial No. 107,044.

This invention relates to combined typewriting and computing machines, such as illustrated in the patent to Hanson, 1,278,812, of September 10, 1918.

5 A statement-sheet and a ledger-sheet with a sheet of carbon interposed are inserted around the platen of the typewriter, and the amounts which are typed upon the sheets are either added or subtracted in the computing mechanism. The machine is provided with a bichrome ribbon having an upper black field, and a lower red field; the black field usually indicating that amounts have been added in the register, and the red field indicating that amounts have been subtracted from the register. The mechanism which shifts the ribbon to either of its fields is automatically controlled by the setting of the machine for either addition or subtraction.

10 In order that amounts may be typed in a column of the work-sheet representing a credit-balance, there is provided a credit-balance-key which is effective to set the machine for subtraction, and to set the ribbon-mechanism to print in red regardless of its previous setting. In this manner it is easy to distinguish a debit or a credit balance. However, since the difference in color to indicate the character of a computation appears only on

15 the statement-sheet, all the amounts in the balance-column on the ledger-sheet being manifolded in black, it will be seen that it is easy when reading a ledger-sheet to read a credit-balance for a debit-balance, which is

20 objectionable.

According to certain features of this invention, there is provided a special credit sign or symbol type-bar which is operated by a special or tell-tale key immediately after a credit-balance computation, to type the character of the computation on the ledger-sheet.

In order to compel the operator to depress said tell-tale key the credit-balance-key is locked as heretofore, and to release the lock it is necessary to depress the tell-tale key. It will be seen that this arrangement renders errors very difficult, because, in case the operator forgets to type the distinguishing character after typing a credit-balance, the next computation will be erroneously typed in red,

and it will thus be evident to the inspector that the credit-balance-key has not been released. The depression of the tell-tale key therefore cannot be avoided.

Other features and advantages will hereinafter appear.

In the accompanying drawings,

Figure 1 is a cross-sectional view in elevation through the center of an Underwood-Hanson machine and shows the invention applied thereto. This view shows the credit-balance-key in its released position, and the special credit-balance type-bar in its normal position.

Figure 2 is an enlarged side view showing the depressed credit-key and its immediate connections.

Figure 3 is a plan view of the mechanism shown in Figure 2.

Figure 4 is a perspective view showing some of the parts of the computing mechanism in their normal positions.

Figure 5 is a view of the credit-balance-key locked in its depressed position.

Figure 6 is an enlarged view showing the face of the special "CR" type-head.

The Underwood-Hanson machine is provided with depressible keys 10 which swing their associated levers 11, and which by means of bell-crank 12 are effective in turn to swing type-bars 13 pivotally mounted at 14. The machine has also a row of numeral-keys 15 which besides being effective to swing their numeral type-bars are also effective to vibrate, by means of links 16, co-operating bars 17 in a setting frame 18.

The computing mechanism consists of a series of rack-bars 19, each having a series of pins 20 settable by means of the bars 17. However, in order that the bars 17 may operate the pins 20, it is necessary to advance the rack-bars 19 to pin-setting position, and this is accomplished by means of dogs 21 carried by a bar 22 mounted at the rear of the carriage. The dogs are arranged to swing levers 23 which, by means of associated links 24, transposing devices 25 and intermediate levers 26, force the rack-bars 19 forwardly to pin-setting position. The pins in the rack-bars 19 are set one at a time as the carriage

is moved in letter-space direction, and after typing the last character of each computation, the motor is tripped by means of a motor-starting bar 27 which forces a link 28 downwardly, thereby rocking a lever 29 which permits a driving wheel, not shown, to rotate a full revolution. The driving wheel in turn reciprocates a general operator 30 which carries forward all the rack-bars 19 corresponding to the denominations of the depressed pins. Said bars 19 engage with denomination-wheels 31 by means of gears 32, thereby rotating the wheels to expose the corresponding numbers through an opening 33.

The setting frame 18 is normally positioned to set pins corresponding to the typed numbers, but may be shifted to a position in which a complement of the typed numbers may be set, in which case, upon operation of the general operator 30, the amounts set will be subtracted from the register, in a manner such as described in said Hanson patent.

In order to characterize the amount subtracted from the register, there is provided a mechanism which is effective to shift the ribbon to its red field, thereby typing the amount in red. Said mechanism is associated with a subtraction-bar 34, which is actuated by a spring 35 when a subtraction-key 36 is depressed. The ribbon-shifting mechanism includes a lever 37, fast to a rock-shaft 38, which carries an arm 39, operatively connected to swing a link 40, thereby co-operating with other mechanism generally indicated by the numeral 41, fully disclosed in the patent to Kupetz, 1,452,162, of April 17, 1923.

In order that a credit-balance may be typed on the work-sheet in red, and the amount cleared from the register, there is provided a credit-balance-key 42, which is actuated against the tension of a spring 43. Said key is effective to cycle the machine, to thereby restore the subtraction-bar 34, and also to shift the ribbon to its red field by means of a bell-crank 44 pivotally mounted at 45. The motor-bar is depressed by means of stud 46 on the credit-balance key which engages a cam-face 47 on a trip-pawl 48, which pawl forms an integral part with an arm 49 pivotally mounted at 50. Said arm 49 carries at the end thereof a stud 51 which engages with the lower end of a slot 52 in the motor-starting bar 27. After actuating the credit-balance key 42, the stud 46 is latched by the pawl 48 by the tension of a spring 53 which restores the motor-starting bar. The latched position of the credit-balance-key is shown in Figure 5.

In the above-mentioned patent to Kupetz, means are provided whereby the cycling of the general operator automatically vibrates the pawl 48 to release the credit-balance key, but for the purposes of the present invention the Kupetz general operator connections to release the credit-balance key are discarded

and the release of the credit-balance key can only be effected by the actuation of the motor-starting key or by a symbol typing key presently to be described.

One function of the credit-balance-key is to prevent the automatic starting of the motor when the carriage comes to a predetermined column-position, and also to prevent the shifting of the computing mechanism from addition to subtraction in case the carriage enters a subtraction zone while said key is actuated. To this end, there is provided a lever 54, which is engaged by an extension 55 of the credit-balance-key so as to force a pawl 56 into engagement with a pin 57 carried by a bell-crank 58 mounted to rock on a shaft 59, but operative to rock said shaft by a dog 58a. Said shaft 59 has a pawl 60 fast thereto, which pawl serves as a means for holding the subtraction-bar 34 in its ineffective position. Said pawl 60 engages a notch 61 in the subtraction-bar 34, and may be swung out of engagement with said notch either by means of the subtraction-key 36 which vibrates an arm 62 fixed on the shaft 59, or by means of a carriage movement which depresses a link 63 and associated mechanism, such as described in said patent to Kupetz. The linkage includes tabulating carriage-stops 64 settable mounted on a rack-bar 65 secured to the carriage and cooperative tabulator-stop-bars 66 operated by tabulator-keys 67. One of the stops is provided with an extension, not shown, but may be similar to that shown by Kupetz, which engages with a lever 69 to thereby depress the link 63 to vibrate a reversing bail 70 to withdraw a link 68 and release the bell-crank 58 to swing the pawl 60 out of engagement with the subtraction-bar 34.

The Underwood-Hanson machine is usually provided with a bichrome ribbon having an upper or black field 71, and a lower or red field 72. The colors indicate the character of the computation, and its shifting, from one color to the other, is controlled by the computing mechanism. Black indicates ordinary adding operations, while red indicates ordinary subtraction operations, but red may also indicate an addition when the credit-balance-key is depressed, in which case the amount copied on the work-sheet is added in the register to clear all the computing wheels. According to certain features of the invention, there is provided a special credit-sign type-bar 73 which is operated by a special credit-balance-typing key 74. The purpose of this sign is to indicate on the ledger-sheet which of the amounts represent a credit-balance. In order to compel the operator to depress the special key after each credit-balance computation, there is provided means for releasing the pawl 48 by the actuation of the special key 74 after typing a credit-balance. Said means may include a lever 75,

pivottally mounted on a supporting stud 76 having an extension 77 to engage a rearwardly-extending finger 78, which may be an integral part of the pawl 48. The special key 74 operates a key-lever 79 having a tongue 80, operative to engage a tab 81, forming an integral part of the lever 75. Said lever 75 is held in its normal position by means of a suitable spring 82, secured to the frame by means of the stud 76.

From the above description and a knowledge of the prior art, as disclosed in the beforementioned patent to Kupetz, it will be understood that if the first item to be typed upon the statement-sheet and manifolded to the ledger-sheet is a debit entry, such as merchandise sold, after typing the date of sale and character of the merchandise, the carriage is tabulated to the debit column and the amount typed in black on the statement-sheet and manifolded in black upon the ledger-sheet, the amount set up on the pin-bars, and the motor-starting key is actuated to cycle the general operator to carry the set-up pin values into the register and subsequently clear the setting of the pins on the pin-bars. The carriage is now tabulated to the balance column where the amount read from the register is typed. If this is the only item to be typed and posted, the subtraction key is actuated before typing the balance, to set the computing mechanism to a subtractive state and a red ribbon field, but as the entry to be typed in the balance column is a debit entry to be typed in black, the credit-balance key is now actuated to reshift the red ribbon set by the subtraction key back to a black field, and the typing of the amount in the balance column in black provides a complementary setting of the pins which, when the general operator cycles, clears the register wheels.

If the first posting on a statement-sheet and ledger also includes a credit item, as for a cash payment, the amount of the debit item will be carried over in the register and not cleared by the credit-balance key, and the debit amount typed in the balance column under a non-add setting of the computing mechanism in a well-known manner, after which the carriage is restored and the platen line-spaced. The second item is posted as "cash" and the carriage is tabulated to the credit column. As this item is to be a credit typed in red and is to be subtracted from the register, the actuation of the subtraction key sets the computing mechanism to a subtractive state and a red ribbon field, so that the typing of the cash amount in the credit column provides a complementary pin set-up which is effective when the general operator is cycled to deduct the cash amount from the debit amount already registered, and the mechanism is restored to a normal black addition.

If the cash item is less than the debit item, the entry in the balance column will be in

black, as already described, but if the cash item is greater than the registered debit, it is clear that a credit balance exists, and when the credit balance amount is read on the register, it must be typed in red on the balance column to be distinguishable at a glance from the debit item, previously typed in the same column. After the carriage has been tabulated to the balance column, the actuation of the credit-balance key sets the computing mechanism to a subtractive state and shifts the ribbon to a red field, and after typing the amount recorded in the register in red, the general operator clears the register, but the ribbon still remains in its shifted red field position, because the credit-balance key remains locked. To release the credit-balance key, the credit key is actuated to type a credit symbol in red after the last numeral typed in the balance column, which typing of the symbol operates to release the locked credit-balance key, and simultaneously actuates the motor-starting key to cycle the mechanism to a normal additive state. The typing of these two items in the balance column renders the statement-sheet self-explanatory through the use of the bichrome ribbon in typing debit entries in black and credit entries in red. As the ledger-sheet records are manifolded through a carbon-inlay, all the items typed in the balance column must necessarily be black, but the typing of the credit symbol "CR" after each credit balance typed, renders the ledger-sheet items in the balance column readily distinguishable.

From this description it is obvious that were it not for the typing of the distinguishing character after the credit-balance item, the machine would remain set for subtraction and the ribbon set to a red field, which might not be noticed by the operator until the typed statement-sheet had been removed and a new work-sheet inserted and typed upon, thus involving errors that are annoying and difficult to correct; that the cycling of the general operator does not release the locked credit-balance key; and that the credit-balance key must be released by the actuation of the motor-starting key at such times when the typing of the credit-balance symbol may not be desirable.

Variations may be resorted to within the scope of the invention, and portions of the improvements may be used without others.

Having thus described our invention, we claim:

1. In a typewriting and computing machine having a computing mechanism, a credit-balance key for setting a computative state for the computing mechanism, a lock for holding said credit-balance key in this actuated position, and a type-bar for typing a credit-balance symbol, the combination with a credit key for operating said symbol type-bar, of means operated by said credit key

- when typing a credit-balance symbol to release the credit-balance key, said means including a pawl that engages the credit-balance key and a spring for maintaining said pawl in engagement with the actuated credit-balance key, said credit key being operative to engage said pawl and release the credit-balance key.
2. In a typewriting and computing machine having a computing mechanism normally set for addition, a subtraction-key for automatically setting the machine for subtraction, a general operator for automatically resetting the computing mechanism for addition after each subtracting computation, a credit-balance key, means controlled by said credit-balance key for cycling the general operator, and a lock for holding the actuated operator, and a credit-balance type-bar, the combination with a special key for operating said type-bar to type a credit-balance sign, of means controlled by said special key operative to release the locked-up credit-balance key, said last means being also effective, when releasing the credit-balance key, to cycle the general operator after the typing of the credit-balance sign.
3. In a typewriting and computing machine having a computing mechanism, a credit-balance-key for establishing a computational state in the computing mechanism, automatic means for locking said credit-balance-key in its actuated position, and a type-bar for typing a credit-balance-symbol, the combination with a special key for operating said type-bar, of means operated by said special key for releasing the credit-balance-key upon operation of said symbol-typing key.
4. In a typewriting and computing machine having a computing mechanism normally set for addition, a traveling carriage operative to determine a computing zone and to shift the computing mechanism for subtraction, a credit-balance-key operative to restore the carriage-set subtraction-mechanism, and means for locking said credit-balance-key when actuated, the combination with a special key, of a special type-bar having a symbol characteristic of a credit-balance computation, said credit-balance-key-locking means being releasable by the special key in typing, after typing the credit-balance-symbol.
5. In a typewriting and computing machine having a general operator to cycle the computing mechanism, a credit-balance key operative to cycle the general operator, and a lock for holding said key when actuated, the combination with a special credit-balance type-bar, of a special key for operating said type-bar to type a credit-balance symbol, and means controlled by said special key in typing the symbol, to effect the release of the credit-balance key and cycle the general operator to restore the computing mechanism after the typing of each credit-balance symbol.
6. In a typewriting and computing machine having a computing mechanism, a general operator therefor, a bichrome ribbon-mechanism, a credit-balance key operable to set the computing mechanism for a red subtraction, means for locking said key in its actuated state during a computing interval, and a type-bar having a credit-balance symbol, the combination with a special key, of means operable thereby to jointly type a red credit-balance symbol, release the credit-balance key, and cycle the general operator to set the computing mechanism for a black addition.
7. In a typewriting and computing machine having a computing mechanism, a bichrome ribbon mechanism, a credit-balance key operable to shift the ribbon to a red field and the computing mechanism to a subtractive state, and automatic means for locking the actuated credit-balance key during typing and computing, the combination with a typing key, of means subsequently operable thereby to type a credit symbol, and also effective to release said credit-balance key, thereby to restore the ribbon and computing mechanism to normal condition for typing in black and performing addition.
8. In a typewriting and computing machine having a power-driven locked-up general operator for cycling a computing mechanism after a computation, the combination with a type-bar and a key to swing said type-bar to print, of means actuated by said key in typing and automatically operable to release the general operator to its driving means to cycle the computing mechanism after the typing of a character.
